(57) **CLAIM**

The ornamental design for an eyeglasses temple with slot, substantially as shown and described.

DESCRIPTION

FIG. 1 is a perspective view of an eyeglasses temple with slot in accordance with the design.

FIG. 2 is a front view thereof.

FIG. 3 is a left side view thereof, with the right view being substantially identical thereto.

FIG. 4 is a top view thereof.

FIG. 5 is a rear view thereof; and,

FIG. 6 is a bottom view thereof.

The broken lines showing environment structure are for illustrative purposes and form no part of the claimed design.
